DESIGN FOR A DOOR PLATE

Maynard S. Holmquist, Seattle, Wash.

Application November 19, 1945, Serial No. 123,885

Term of patent 3½ years

(Cl. D1—7)

To all whom it may concern:

Be it known that I, Maynard S. Holmquist, a citizen of the United States, residing at Seattle, King County, Washington, have invented a new, original, and ornamental Design for Door Plate, of which the following is a specification, reference being had to the accompanying drawings, forming part thereof, wherein—

Fig. 1 is a perspective view of a door plate embodying my new design.

Fig. 2 is a front view of the same.

Fig. 3 is an edge view of the same.

I claim:

The ornamental design for a door plate, as shown.

MAYNARD S. HOLMQUIST.
